UNITED STATES PATENT OFFICE.

LEON B. YEISER, OF CLEVELAND, OHIO.

FLUSHING-TANK.

No. 924,953.

Specification of Letters Patent.

Patented June 15, 1909.

Application filed April 3, 1908. Serial No. 425,050.

To all whom it may concern:

Be it known that I, LEON B. YEISER, a citizen of the United States, and resident of Cleveland, Ohio, have invented certain new and useful Improvements in Flushing-Tanks, of which the following is a specification containing a full, clear, and exact description, reference being had to the accompanying drawings, forming a part hereof.

10 My invention relates generally to flushing tanks, and more particularly to a combined silence chamber and after fill for flushing tanks, whereby the action of the water discharged into the tank is made perfectly 15 noiseless, and the after fill providing means whereby sufficient water is delivered to the closet valve trap to form a perfect seal therein.

20 To the above purposes, my invention consists in certain novel features of construction and arrangement of parts, which will be hereinafter more fully set forth, pointed out in the claims, and illustrated in the accompanying drawings, in which:

25 Figure 1 is a vertical section taken through the center of a flushing tank constructed in accordance with my invention; Fig. 2 is a detail section taken on the line 2—2 of Fig. 1; Fig. 3 is a plan view of the silence chamber; 30 Fig. 4 is a vertical section taken on the line 4—4 of Fig. 3; and Fig. 5 is a horizontal section taken on the line 5—5 of Fig. 4.

Referring by numerals to the accompanying drawings: 1 designates the body of the 35 flushing tank, 2 the water supply pipe provided with the usual inlet valve 3, operated by a float, and arranged in the bottom of the tank is the outlet or discharge valve housing 4, normally closed by the usual discharge 40 valve 5, which is usually in the form of a rubber ball. All of the parts just described are of ordinary well known construction, and form no part of my invention.

45 Formed integral with the outlet valve housing below the valve seat is a hollow extension 6, into which is fitted the lower end of a vertically disposed over flow tube 7, and seated in the upper end thereof is a hollow member 8, which forms the silence chamber, 50 and through the center of which member extends a vertically disposed tube 9, with which the upper end of the tube 7 communicates. Connected to the side of this silence chamber 8 is a horizontally disposed tube 10, the opposite end of which is connected to the inlet

valve housing 3, and formed in the tube 9, directly opposite the end of this tube 10 is an aperture 11. Leading from the side of the silence chamber 8 downward to a point adjacent the bottom of the tank 1 is a tube 12, which allows the water delivered to the silence chamber to discharge into the tank 1. 60

The operation of my improved flushing tank is as follows: When the valve 5 is elevated, the water in the tank discharges 65 through the valve housing to flush the bowl in the usual manner, and when this action takes place the float connected to the inlet valve 3 is lowered, thus opening said inlet valve, and water from the supply pipe 2 will 70 now pass through the open inlet valve, from thence through the tube 10 to the silence chamber 8. Owing to the use of the silence chamber, the pressure of the water entering 75 said chamber is relieved, and the noise incident to the discharge of said water is muffled or deadened within said silence chamber, and said water finally discharges through the tube 12 to the interior of the tank 1. When the water rises in said tank to such a degree 80 as to elevate the float connected to the inlet valve 3, said valve will be closed thereby, shutting off the supply of water to the tank, and in order to insure sufficient water to 85 form a seal in the trap below the bowl, the aperture 11 is provided, which permits water to pass downward through the overflow tube 7, from thence through the hollow extension 6 of the valve housing 4, and from thence 90 downward through the tubular connections to the trap. Should there be any leakage of water through the inlet valve 3, the excess of water coming into the tank 1 will discharge through the tube 9 in the center of the silence chamber, and will pass down through the 95 over flow tube and be carried to the trap beneath the tank.

The silence chamber and after fill of my improved construction is very simple and inexpensive, is applicable for use for all 100 forms of flushing tanks, will operate under any water pressure, takes care of any leakage of the inlet valve in the tank, and insures sufficient water in the trap beneath the bowl to form a perfect seal. 105

I claim:

1. The combination with a flushing tank provided with the usual supply and outlet pipes, of a tubular connection from the supply pipe to the outlet pipe, a silence chamber 110

- arranged in the tubular connection, and there being an outlet from the silence chamber to the interior of the tank.
2. The combination with a flushing tank provided with the usual inlet and outlet pipes, of an annular housing arranged in the tank between the pipes, a tubular connection from the inlet pipe to the annular housing, a tubular connection from the opening in the center of the annular housing to the outlet pipe, and there being an aperture formed through the inner wall of the annular housing, and there being an outlet from the annular housing to the interior of the tank.
3. An attachment for flushing tanks provided with the usual inlet and outlet pipes, comprising a housing through which is formed an opening, and which housing is connected to the inlet pipe of the tank, a tubular connection from the opening in the housing to the outlet pipe of the tank, there being an opening formed through the inner wall of the housing to establish communication from the interior of the housing to the pipe leading to the outlet pipe, and an outlet pipe leading from the housing to the interior of the tank.
4. The combination with a flushing tank provided with the usual inlet and outlet pipes and with the usual over flow tube connected to the outlet pipe, of an annular housing arranged on the over flow tube, a tubular connection from the inlet pipe to the annular housing, there being an outlet formed through the outer wall of the annular housing, and there being an aperture formed through the inner wall of the housing.
5. A combined silence chamber and after fill for flushing tanks, comprising an annular housing, provided with an opening which is connected to the inlet pipe of the tank, there being an opening formed through the inner wall of the housing to establish communication from the interior of the housing with the opening through said housing, and there being a water outlet formed through the side of the housing.

In testimony whereof, I have signed my name to this specification, in presence of two subscribing witnesses.

LEON B. YEISER.
